(57) **CLAIM**

The ornamental design for a flag, as shown and described.

DESCRIPTION

FIG. 1 is a front elevational view of the flag of the present invention, the rear view being a mirror image thereof; FIG. 2 is a left side elevational view of the flag of FIG. 1; FIG. 3 is a right side elevational view of the flag of FIG. 1; FIG. 4 is a top plan view of the flag of FIG. 1, the bottom view being a mirror image thereof; and, FIG. 5 is a top, front, left side perspective view (in a slightly altered position).

The broken lines showing of a foreign flag in FIGS. 1 and 5 are for illustrative purposes only and form no part of the claimed design.
